CLAIM

The ornamental design for a piercing probe tip as shown and described.

DESCRIPTION

FIG. 1 is a perspective view of a piercing probe tip;
FIG. 2 is a bottom plan view of the piercing probe tip shown in FIG. 1;

FIG. 3 is a top plan view thereof;
FIG. 4 is a front side elevational view thereof;
FIG. 5 is a rear side elevational view thereof;

(Continued)

FIG. 6 is a right side elevational view thereof; and,
FIG. 7 is an exploded perspective view thereof.
A left side elevational view of the piercing probe tip is not
shown because it is a mirror image of the right side eleva-
tional view shown in FIG. 6. The broken lines in the
drawings form no part of the claimed design.
